(57) **CLAIM**

The ornamental design for a beverage container filling station as shown and described.

DESCRIPTION

FIG. 1 is a top, front, right side perspective view of a beverage container filling station showing our new design; FIG. 2 is a bottom, rear, left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a top, front, right side perspective view thereof, showing an environment including a beverage container. The broken lines illustrate portions of the environment that form no part of the claimed design. Shading lines shown in the drawings represent surface contours and not surface ornamentation.
